UNITED STATES PATENT OFFICE.

EUGENE J. McCARTY, OF CLINTON, MASSACHUSETTS.

VALVE.

966,040.

Specification of Letters Patent. Patented Aug. 2, 1910.

Application filed August 27, 1908. Serial No. 450,473.

To all whom it may concern:

Be it known that I, EUGENE J. McCARTY, a citizen of the United States, residing at Clinton, in the county of Worcester and State of Massachusetts, have invented a new and useful Valve, of which the following is a specification.

This invention relates to valves, and while capable of general use, certain features thereof are particularly applicable to globe valves.

The principal objects of the invention are to provide such a construction and method of manufacture that the valve can be made out of a plurality of pieces of sheet steel, thus eliminating the foundry work usually required for the valves on the market, and also avoiding the use of expensive composition metals for the entire valve casing; also to provide a construction in which with a single set of dies valves of several different forms can be produced; also to provide an improved form of valve and valve stem particularly suited for use with a sheet metal casing. The invention also comprises various improvements in the details of construction.

Further objects and advantages of the invention will appear hereinafter.

Reference is to be had to the accompanying drawing, in which—

Figure 1 is a side elevation of a globe valve constructed according to this invention; Fig. 2 is a longitudinal sectional view of the same; and Fig. 3 is an elevation of a valve constructed like that shown in Fig. 1, but with one of the parts reversed so as to alter the shape of the valve, and also showing other modifications, Fig. 4 is a side elevation of a modified form.

A globe valve constructed according to this invention has a casing preferably consisting of two main members 10 and 11 which are in a sense complementary to each other, and an intermediate member 12. Each of these members is preferably formed of sheet steel and shaped up in dies. The members 10 and 11 are provided with flanges 13 and 14 respectively, which are located at an angle of 45 degrees to the axes of the inlets and outlets 15 thereof. These flanges preferably extend outwardly and are circular in shape. The intermediate member 12 consists of a disk of sheet steel of circular form and of the same size as the outer pe-

riphery of said flanges and is stamped up to form a perforation 16 therein. It is provided with a valve seat which may be integral with the walls of the disk, or as shown in Fig. 2, it may consist of a piece of composition, bronze, nickel bronze, or the like 17 set on the disk and electrically welded or otherwise secured thereto. The ends of the valve 18 may be castings screwed on to the outsides of the outlets and inlets 15 as shown in Figs. 1 and 2, or they may be welded or otherwise secured to form flanges 19 as shown in Fig. 3. The edges of the disk are secured to the flanges preferably by electrical welding in the form shown in Figs. 1 and 2, or they may be bolted or riveted as shown in Fig. 3. Riveting is especially suitable for large sizes. It will be seen that in assembling the parts the disk 12 can be placed against the flange 14 and then the flange 13 can be placed against the other side of the disk, and the member 10 turned on the axis of said flange until it comes to the proper position, and then the parts are secured together in any desired way. In this way it will be seen that with a single set of dies for each member a large variation may be made in the shapes and sizes of valves to be produced. On account of the angle of 45 degrees of the flanges the member 10 can be turned to various angles so as to produce elbows, T's, and the like, one of the forms in which it can be applied being shown in Fig. 3, and another in Fig. 4.

It will be understood, of course, that while 45 degrees is a most convenient angle, yet any other angle may be adopted according to the necessities of the case. In order to further change the angle between the outlets 15, another plan can be adopted according to this invention. This consists in forming the members 10 and 11 in the same way as indicated above, and leaving the member 11 in its original shape, but altering the flange 13 so as to permit the two members 10 and 11 to be put together with the outlets at varying angles to each other. This is preferably done by turning the flange 13 back in dies or in any other desired way, starting at either the upper or lower edge and working toward the opposite edge on a predetermined angle. In the form indicated in Fig. 1 the member 10 is shown in the position which it would occupy when connected up as indicated above, and in Fig. 4 the same

member is shown with the flange turned back in this way so as to alter the angle slightly. When this is done all that is necessary to do is to trim off the flange around 5 the edge and then unite the pieces as indicated above. Thus a large number of modifications can be made without changing the original dies.

The member 11 is provided with a cylindrical portion 20 which is screw threaded, and on this is movably mounted a member 21 which is preferably made of sheet steel, a packing 22 being employed as will be readily understood. A valve stem 23 is 10 passed down through the member 21, and provided with a circumferential groove 24. The member 21 is then pressed in at 25 to form an annular depression which projects into the groove inside and forms a bearing permitting the valve stem to be turned without moving longitudinally. The valve stem is provided with a screw thread 26 which fits an internally screw-threaded projection 27 on the back of a valve 28. This valve is 15 shown as provided with a composition face 30, and it is preferably guided so that it cannot turn by a guide 31. By this construction a non-rotatable valve is provided which will not unnecessarily wear the seat, and a most convenient, simple, and inexpensive construction is secured.

It will be understood that while I have illustrated a globe valve, many features of the invention are equally applicable to other forms of valves, and I do not wish to be restricted thereto. I am also aware that many other modifications may be made in the construction and manufacture of the device without departing from the scope of the invention as expressed in the claims. Therefore, I do not wish to be limited to all the details of construction shown and described, but

What I do claim is:—

1. The method of making a globe valve which consists in forming up two pieces of sheet metal in dies into a general hemispherical shape, each having a circular edge and a tubular projection opposite the edge in such position that when the edges are placed together said projections will be in diametrical alinement, turning the edge of one of said members back on an angle so as to bring said edge into a plane at a new angle to the axis of said projection, placing a disk-shaped sheet metal member having a valve-seat thereon between said first two members with the edges of said first two members in contact with the opposite sides of the disk-shaped member, and then uniting said edges with the disk-shaped member.

2. The method of making a valve which consists in placing a tubular member on the valve chamber proper, placing in said tubular member a valve-stem having an annular

groove and forming an annular depression on the outside of said tubular member while the valve-stem is in place projecting into said groove so as to hold the valve-stem in position.

3. The method of making a valve which consists in forming the valve chamber from a plurality of pieces of sheet metal, welding said pieces together, placing a tubular member upon one of said members, and a valve 70 stem in said tubular member, said valve stem having an annular groove, and forming an annular depression on the outside of said tubular member so as to form a bead inside the same projecting inside said groove. 80

4. In a valve, the combination of a valve chamber consisting of three pieces of sheet steel and having a valve seat therein, of a sheet metal tubular member secured on one of said pieces and having a circular projection in the neck thereof, a valve stem extending through said sheet metal member and having an annular groove therein fitting said projection, whereby said valve stem may be turned therein without moving it longitudinally, said valve stem having a screw thread on the end thereof, a valve consisting of a disk provided with an internally screw-threaded projection fitting the thread on the stem, and a guide for said valve. 95

5. In a valve, the combination of a casing, a member adapted to be secured thereto and having an internal circular bead or projection, a valve stem having an annular groove fitting in said bead and provided with a 100 screw thread, a valve having a composition valve surface and provided with a rear projection internally threaded to fit said screw, and a guide for the valve, whereby the turning of the valve stem will result in longitudinal motion of the valve without rotating it. 105

6. As an article of manufacture, a globe valve formed of sheet steel and having a 110 perforated inner partition, and a composite valve seat welded on said partition over the perforation thereof.

7. In a valve, the combination with a valve chamber, of a sheet metal tubular member secured thereon and having an interior 115 circular projection in the neck thereof, a valve stem extending through said sheet metal member and having an annular groove therein for receiving said projection, whereby said valve-stem can be turned therein 120 without moving longitudinally, said valve-stem having a screw-thread on the end thereof, and a valve provided with an internally screw-threaded projection fitting the thread on the stem. 125

8. In a valve, the combination with a valve chamber, of a sheet metal tubular member secured thereon and having an interior circular projection in the neck thereof, a valve stem extending through said sheet metal 130

member and having an annular groove therein for receiving said projection, whereby said valve-stem can be turned therein without moving longitudinally.

- 5 9. In a valve, the combination of two sheet steel complementary members, a sheet steel disk welded to both of said members and extending through them and provided with a perforation near the center thereof, a com-
10 position valve seat welded on the flat sur-

face of said sheet steel disk over the perforation, and a valve for said seat.

In testimony whereof I have hereunto set my hand, in the presence of two subscribing witnesses.

EUGENE J. McCARTY.
